WELL BAILER

Felix H. Eckert, San Antonio, Tex.

Application January 18, 1941, Serial No. 375,059

2 Claims. (Cl. 166—19)

This invention relates to well bailers and has for its object the more efficient removal of sand and other accumulations in the bottoms of oil wells which have caused the wells to cease flowing.

Another object is to utilize the fluid under pressure above the accumulated material for the purpose of filling the bailer.

A further object is to provide a bailer which can be applied at any point in the well below the fluid level and above the well bottom, a new and novel arrangement of slips being employed for cooperation with the inner wall of the casing or the oil tubing string.

With the foregoing and other objects in view which will appear as the description proceeds, the invention consists of certain novel details of construction and combinations of parts hereinafter more fully described and pointed out in the claims, it being understood that changes may be made in the construction and arrangement of parts without departing from the spirit of the invention as claimed.

In the accompanying drawings the preferred form of the invention has been shown.

In said drawings

Figure 1 is a front elevation of the bailer, a portion being removed.

Figure 2 is a side elevation of the structure shown in Figure 1.

Figure 3 is an enlarged central longitudinal section through the bailer tube and cylinder and their valves.

Figure 4 is a view of a portion of the bailer and showing the relative positions of the parts on the completion of the initial upward pull effected during the operation of anchoring the bailer in the well casing.

Figure 5 is a view similar to Figure 4 showing the relative positions of the parts during the next step in the operation of anchoring the bailer in a casing at which time the bailer is lowered so that the toothed slips will be held supported by the bowed spring elements so as to become engaged with the inner surface of the casing.

Figure 6 is an enlarged section on line 6—6, Figure 4.

Figure 7 is an enlarged section on line 7—7, Figure 4.

Figure 8 is an enlarged section on line 8—8, Figure 4.

Figure 9 is an elevation of the toothed face of one of the slips.

Referring to the figures by characters of ref-

erence, 1 designates the elongated bailer tube closed at its lower end as shown at 2 where it is surrounded by an annular shoulder 3 constituting a valve. Adjacent to this closed end the tube is provided with diametrically opposed intake slots or ports 4.

The other or upper end of tube 1 can be formed with the usual threaded portion 5 constituting a portion of a tool joint and this can be detachably engaged by a collar 6 which serves to join the tube to the lower end of a valve casing 7. This casing has a loop 8 extending upwardly therefrom for engagement by one end of a wire line whereby the bailer can be raised and lowered in a well.

A nipple 9 opens into the lower portion of the casing 7 and is extended downwardly in collar 6 toward the tube 1. The upper end of this nipple provides a seat for a ball valve 10 engaged by the lower end of a coiled spring 11. This spring is located in the casing 7 and its upper end is engaged by the foot 12 of a screw 13 which is adjustably mounted in the upper end of the casing 7 and is adapted to be turned for the purpose of increasing or reducing the compression of the spring 11, thereby to increase or reduce the pressure of the valve 10 on its seat.

The tube 1 extends through a stuffing box 14 located in the upper end portion of a cylinder 15. This cylinder has an extension 16 at its lower end detachably joined to a tip or coupling 17 which can be internally screw-threaded as shown. Extension 16 is provided with diametrically opposed slots 18 constituting intake ports. A portion of the lower end of cylinder 15 is exposed within extension 16 to form an annular valve seat 19 and this seat is so located that it can be engaged by the valve shoulder 3 when the tube 1 and cylinder 15 are moved relative to each other. For the purpose of limiting this relative sliding movement of these parts, a longitudinal slot 20 is formed in the cylinder, this slot being somewhat longer than the slots 18. Into the slot projects a stud 21 projecting from the tube 1.

A coiled spring 22 is mounted on the tube 1 and bears at one end against the stuffing box 14 while its other end bears against the annular shoulder 23 provided at the lower end of the joint portion 5.

Removably seated within the tip 17 of the extension 16 is the tubular neck 24 of a yoke 25 through which is extended a longitudinal bore 55 26. Extending along this bore and terminating

inwardly from the ends of the yoke are diametrically opposed slots 27. Each of these slots has longitudinal grooves 28 in its side walls and those outer faces of the yoke through which the slots open converge downwardly along straight lines as shown at 29.

Slidably mounted within each of the slots 27 and along the adjacent inclined faces 29, are slips 30 the outer faces of which are formed with ratchet teeth 31 while the sides of each slip have oppositely extending longitudinal ribs 32 adapted to work within the grooves 28. A loop 33 is extended downwardly from each of the slips and projecting through the opposed slots and through the loops on the respective slips is a pin 34 extended diametrically through the upper end of a rod 35. This pin is held against accidental separation from the rod by means of a set screw 36 and the lower or free end portion of the rod has a head or enlarged portion 37 and a longitudinal recess 38. In this recess is positioned a spring latch 39. This latch is adapted to normally support a ring 40, diametrically opposed portions of which are joined to the lower ends of bowed springs 41. The upper ends of these springs are joined to separate rings 42 which are mounted loosely on the rod one above the other. The weight of the rings 40 and 42 and of the springs 41 is not sufficient to force the latch 39 back into the groove 38 and, consequently, under normal conditions this latch will hold the ring 40 elevated.

When it is desired to use the bailer at a point above the bottom of the well, the parts, assembled as in Figures 1 and 2, are lowered into the well casing by means of a wire line attached to the loop 8. The arcuate spring elements are normally flexed outwardly, as in Figure 4, just sufficiently to contact the inner wall of the well casing or tubing but to descend with the bailer without causing ring 40 to slip past and under the latch 39. During this operation the rings 42 will be brought close to the lower end of the yoke 25. When the bailer reaches the desired depth the downward movement thereof is stopped and the bailer is then raised about eight inches. When this is done the arcuate springs 41, through their frictional contact with the inner surface of the casing, will be restrained so that the latch 39 will be pulled upwardly through ring 40 and snapped into engagement therewith as shown in Figure 4. By then suddenly slackening the supporting wire line, the bailer tube, cylinder and yoke will all move downwardly relative to the supported rod 35 with the result that this rod will transmit a thrust through pin 34 to the slips 30, causing the teeth thereon to bite into the inner surface of the casing or tubing. The cylinder of the bailer is thus held securely at the desired level. The bailer tube 1 is then lowered by slackening the wire line. This will cause the valve shoulder 3 to move away from its seat 19 at the position shown in Figure 3 to a position below ports 18. Thus the ports 4 will be brought into register with the ports 18 and fluid under pressure and surrounding the bailer will rush through these ports into tube 1 and rise in the tube until the pressure in the tube is equal to that of the fluid surrounding the bailer. The tube 1 is then pulled upwardly, causing valve 3 to engage its seat 19 and thus raising the bailer filled with fluid to a point outside of the well. The bailer is then lowered into the slush pit generally provided, the lower end of the rod 35 being brought against the bottom of the pit. Thus the weight of the bailer tube 1 causes the tube to move downwardly into the

cylinder and open the ports 4 to the ports 18. During this movement air in the tube 1 is trapped and placed under great pressure so that as soon as the ports are opened, the fluid contents of the bailer are ejected by this air under pressure with great force.

It is to be understood of course that the spring 11 which holds the ball valve 10 to its seat is adjusted to withstand a greater pressure than that which would be exerted by the air and liquid contents of the bailer during the foregoing operation.

Should it be desired to use the bailer on the bottom of a well, the yoke 25 and the parts carried thereby can be dispensed with. In that event, when the bailer is lowered into the well the lower end of the cylinder tip 17 will be brought to a rest upon the bottom of the well or the accumulations thereon and further downward movement of the wire line will result in the tube 1 moving under its own weight from the position shown in Figure 3 to its other extreme position. Thus the fluid will rush through the ports into the tube 1 and when the tube is pulled upwardly to seat its valve 3 against the seat 19, this fluid will be trapped in the tube. Thereafter when the elevated bail is lowered into the slush pit, the tip 17 is brought against the bottom of the pit and the tube, when lowered, will not only open the ports 4 and 18 but also place air in the tube under pressure so that this compressed air will forcibly eject the contents of the tube through the ports and into the slush pit.

It is to be understood, of course, that the valve casing 7 is provided with a vent 43 so that should the valve become unseated by excessive pressure from within tube 1, the released air can escape from the valve casing.

It is to be further understood that this bailer can be used like an ordinary bailer simply by removing the valve end, and the parts associated therewith.

What is claimed is:

1. In a bailer the combination of a yoke having upwardly diverging faces, opposed slips mounted on said yoke for sliding movement along said upwardly diverging faces, a rod within and projecting below the yoke and mounted for limited sliding movement relative to the yoke, means on one end of the rod and within the yoke for transmitting motion between the rod and slips, a head on the other end of the rod, a latch on the rod adjacent to the head, opposed bowed spring elements slidably mounted on the rod and secured to a ring at their lower ends, said ring initially being yieldably supported by the latch, rings at the upper ends of the spring elements slidably mounted on the rod, said spring elements frictionally engaging the well wall, a cylinder connected to and extending from the yoke and having a slot constituting a port, a bailer tube slidably mounted in the cylinder and having a port normally closed thereby, yieldable means for holding the bailer tube in normal position in the cylinder, said ports being positioned to register when the bailer tube is moved from normal position in the cylinder, and a normally closed valve in the bailer tube positioned to open under pressure from within the tube.

2. The combination of a bailer tube closed at its lower end and having a port in its side wall adjacent said end, a cylinder telescopically mounted on the lower end of the tube and having a slot in its side wall near its lower end arranged to register with the port in the bailer tube to

open the bailer when said tube and cylinder are in telescoped relation, co-engageable valve means on the tube in the cylinder initially held in engagement with each other by said yieldable means when the tube and cylinder are in extended position closing the port in the bailer tube and limiting extended movement of the bailer tube and cylinder, a yoke connected to and depending from the cylinder and having upwardly diverging faces, slips mounted on the yoke for upward movement along said diverging faces, to grip the well wall and anchor the cylinder in the well, a rod slidably mounted within and extending downwardly from the yoke, a coupling pin carried by the rod and slidable within the yoke, loose connections between the slips and coupling pin and cooperating with the pin to provide driving connections between the rod and slips, the rod being enlarged at that end thereof remote from the pin, a spring

latch on the rod adjacent the enlarged portion thereof, a lower ring slidable on the rod, bowed spring elements connected to and extending upwardly from said ring and frictionally engaging the well wall, a separate upper ring connected to the upper end of each of the bowed springs and slidably surrounding the rod, said rod and pin providing a lost motion connection between the bowed spring elements and the slips, said rings and bowed spring elements being initially slidably positioned on said rod above the spring latch to ride upwardly on the rod and engage the lower end of the yoke as the device is being lowered into the well, said bowed spring elements being movable into locked position between the rod and casing to hold the slips stationary to permit the yoke to be moved downwardly relative thereto when it is desired to open the bailer.
